BURR ROLLER

Louis C. Mundt and Albert L. Roco, Houston,
Tex., assignors to Leslie A. Layne, Houston,
Tex.

Application March 31, 1936, Serial No. 71,830

5 Claims. (Cl. 29—66)

The invention relates to a burr roller of the type which will eliminate burrs projecting on the inside of a pipe or other structure.

In the operation of perforating pipe for various purposes where the holes are drilled through the wall of the pipe it is, of course, the usual and customary practice to move the drill toward the center of the pipe. Naturally the drill in penetrating the middle of the hole will leave a small 10 projecting burr around the periphery of the hole which has been drilled, and this is particularly true where speed in operation is maintained and where a gang drill is used.

The invention has a particular application to 15 the removal of the burrs on the inside of perforated pipe which is to be used for screens or strainers in wells.

It is desirable to remove the burrs because 20 such burrs will act as an obstruction in the pipe and encourage the accumulation of silt, sand and otherwise interfere with a more efficient operation of the screen.

Various devices have been provided for removing the burrs on the inside of the pipe, but the 25 present invention has been devised with a view of simplifying the operation and eliminating the burrs throughout the length of the pipe section.

It is one of the objects of the invention to provide a burr roller which may be passed into a section 30 of pipe to smooth off any projecting burrs.

Another object of the invention is to provide a burr roller which carries a plurality of spools which will move outwardly by centrifugal force to strike the burrs with a sufficient impact to remove the burrs.

Another object of the invention is to provide a burr roller with spools which move outwardly by centrifugal force but in which the spools are geared so that the expansion will be uniform with 40 all of the spools.

Another object of the invention is to so connect the several spools of a burr roller that a burr having contact with one of the spools is struck with the centrifugal force which is applied to all 45 of the several spools.

Another object of the invention is to provide in combination with a burr roller a centering device which will hold the roller centralized in the pipe so as to uniformly remove the burrs.

50 Other and further objects of the invention will be readily apparent when the following description is considered in connection with the accompanying drawings wherein:

Fig. 1 is a vertical sectional view of a pipe section in which the burr roller is in operation.

Fig. 2 is a section taken on the line 2—2 of Fig. 1 and illustrating the radial arrangement of the spools.

Fig. 3 is a magnified view of a pipe section illustrating the perforations before and after the 5 passage of the burr roller.

Fig. 4 is an elevation of one of the spools showing the camber thereof.

In Fig. 1 the pipe which is to be operated upon is illustrated generally at 2 and has been perforated with a plurality of openings 3 which have been formed by moving the drill radially inward through the wall of the pipe. Naturally as the drill completes the opening there will be a small amount of the metal material such as 4 which 15 will be distorted and moved inwardly to form a burr such as 5.

Fig. 3 shows a magnified form of this burr wherein the distorted material 4 has been carried inwardly with the drill in order to permit passage 20 of the drill through the opening, it being understood that the general type of drill used for this work is a twist drill. Fig. 3, of course, is magnified considerably in order to emphasize the 25 effect that a burr of this type will have on forming an obstruction on the inside of the pipe and to illustrate diagrammatically the problem which is being solved.

It will be noted that the material 4 has been moved from a position within the opening 3 to a 30 position perpendicular to the wall 6 of the pipe so that there has already been a severe stress placed on the material 4 where it is connected to the wall 2. In other words this material at the corner 7 has been bent beyond its elastic limit 35 because it remains in the position shown in the drawing which is different from its original position. In other words, this material 4 is more or less brittle because it has already been distorted and is quite readily removed by a pounding 40 action. The tendency is for this material 4 to break off at the corner 7 where it joins with the pipe wall 6. The lefthand side of Fig. 3 shows an opening 3 wherein the burr has been removed and the inside surface 10 of the wall 6 is smooth 45 and the burr has been removed as an obstruction.

The machine for removing the burrs is best seen in Fig. 1 and comprises a shaft 15 which has a drive wheel or pulley 16 affixed to one end thereof. It will be understood that this shaft 50 must be of considerable length if it is to project from the pipe 2 because in many instances pipes of this type have a length of twenty or thirty feet and the burr roller must be passed throughout the length of the pipe.

The pulley 16 is provided with an area 17 to receive a belt or other driving mechanism which can be driven from a suitable source of power to impart rotation to the shaft 15. It is desirable that this shaft 15 rotate at a relatively high rate of speed approximating 3000 to 5000 revolutions per minute. The bearing 18 supports the outer end of the shaft in a housing 19 and this housing may be of considerable length and is joined to 5 a sleeve 20 by the threaded connection 21. Another bearing 22 is carried by the sleeve 20 to support the shaft 15 in the sleeve. Any desired number of bearings may be placed along the housing 19 in order to suitably maintain the shaft 15 against excessive vibration.

The inner end of the shaft 15 is carried in a bearing 23 and a stop collar 24 serves to prevent end play of the shaft 15.

A driving head 25 carries a shank 26 which is threaded into the end of the shaft 15 so that it will be compelled to rotate therewith. A shoulder 27 is formed adjacent the shank 26 and is arranged to abut against the end of the shaft 15 so that when the head is screwed tightly into 25 the end of the shaft that the drive torque will be transmitted from the end of the shaft to this shoulder 27.

From this point the head 25 is enlarged to include a plate 28 which forms part of the frame 30 or head. This frame also includes an end member 29 which is spaced from the plate 28 by a plurality of connecting bolts 30. Three such bolts are seen in Fig. 2 and mounted thereon for pivotal movement is an arm 31 and a link 31' 35 which are spaced apart to receive the roller 35 between them. The arm 31 is of particular construction and with the link 31' carries the roller shaft 32. The arm 31 is provided with a plurality of teeth such as 33 on the inner side. As seen 40 in Fig. 2 there are three of these arms, but any desired number may be provided.

Each arm 31 carries a roller 35 on its roller shaft 32 which is preferably of solid metal and will therefore have considerable weight, the inertia of which is available for smoothing the burrs on the inside of the pipe. These rollers are seen in Fig. 1 in elevation and may have a straight cylindrical surface or they may have a cambered or curved surface 37 as seen in Fig. 4. 45 A small pinion gear 40 is pivoted on a stud shaft 41 carried by the plate 28 as seen in Fig. 2 and this pinion has teeth thereon which mesh with the teeth 33 formed on all of the arms 31. It seems obvious from this construction that because of the fact that these arms are geared together in this manner that any swinging movement of one of the arms can only occur when the other arms are permitted to effect a similar swinging movement.

It should be noted that the arms 31 and roller 35 are eccentrically mounted with respect to the shafts 30 so that when the head 25 is rotated the roller will have a tendency to swing circumferentially outward about the shaft 30 as a center. The swinging movement of each arm is limited by the fact that the last tooth on each arm is of greater width as seen at 42 so that it cannot pass between the teeth of the pinion 40.

In order that the entire mechanism will be 70 suitably centered within the pipe 2 a spring actuated centering mechanism is shown generally at 50. This includes a pair of links 51 and 52, the links 52 being pivoted at 53 to a collar 54 which is fixed on the sleeve 20. The link 51 is 75 pivoted at 56 to a sliding collar 57 which is ar-

ranged for telescoping movement on the sleeve 20. The adjacent ends of the links 51 and 52 support a shaft 58 which carries a guide roller 59. There are a plurality of these arrangements carried by the collars 54 and 57 so that they will tend to support the sleeve 20 and the shaft 15 in a centralized position in the middle of the pipe 2.

A spring 60 is confined between the shoulder 61 on the sleeve 20 and the end 62 of the sliding collar 57 so that it normally tends to urge the guide roller 59 radially outward. The amount of pressure exerted by this spring is sufficient to support the roller mechanism in the pipe, it being understood when the machine is forced 15 into the pipe that the guide roller 59 will be compressed.

In operation the mechanism is inserted in the end of the pipe as seen in Fig. 1 and the shaft 15 compelled to rotate at a high rate of speed. 20 Because of the considerable weight of the rollers 35 and the fact that they are eccentrically mounted on the bolts 30 will cause them to swing outwardly by centrifugal force. They will, of course, contact the inside surface 10 of the pipe and 25 inasmuch as they are rotating at a high rate of speed they will strike the burr portions 4 and either flatten the portion down against the inside of the pipe 10 so that it forms little or no obstruction, or by striking the burr a sharp blow 30 will break it from its connection with the wall of the pipe so that the burr is removed completely. This is illustrated by the difference between the two openings in the pipe as seen in Fig. 3, the burr having been removed from the 35 left-hand opening. The same is also illustrated in Fig. 1 where the burr portion 4 is seen on those openings which have not been passed by the roller.

It is to be understood that power from any 40 suitable source may be used to rotate the roller mechanism such as the present shaft, or it may be driven by fluid pressure if desired by incorporating a fluid pressure motor adjacent the head 25 and substituting a pipe for the shaft 45 15 so that fluid pressure can be conducted to the fluid motor.

Particular attention is directed to the fact that all of the rollers are compelled to maintain the same radial distance from the center of rotation. This is of advantage because when one roller strikes a burr that particular roller cannot be moved inwardly by the burr which is struck unless the obstruction is of sufficient strength to overcome the centrifugal force of all three of the rollers, because the roller which strikes the burr starts to move inwardly which compels a turning movement of the pinion 40 which in turn tends to rotate the other arms and rollers inwardly. This coupling together of the several rollers enables the use of a small roller of a suitable weight that it can be rotated at a high speed, yet associating the weight of all of the rollers together for the purpose of striking the blow against the burr. It seems obvious that a blow approximating many hundreds of pounds can be struck by one of these small rollers when it is rotating at a high rate of speed.

Broadly the invention contemplates a high speed rotating head which will serve to eliminate 70 the burrs on the inside of a pipe which has been perforated.

What is claimed is:

1. A burr roller to remove the burrs resulting from the perforation of pipes comprising a head 75

slidable longitudinally in a pipe, a plurality of rollers thereon, means mounting each roller in an eccentric transverse swinging position on said head, said means including an arm, and inter-
5 engaging means on said arms and said head whereby all of said rollers are caused to swing in unison.

2. A burr roller comprising a support, a rotatable head thereon, a plurality of uniformly mov-
10 able means eccentrically mounted on said head to swing outwardly by centrifugal force upon rotation of said head, said means including roller members to strike the burrs adhering to the inside of the pipe and additional means to center said support in the pipe being burred so that all of said means will bear uniformly on the inside of the pipe.

15 3. In a burr roller, a rotatable head, a plurality of burr rollers mounted thereon to swing outwardly against the burrs due to centrifugal force upon rotation of said head, and means to control all of said rollers so that the swinging

movement is uniform, the mountings for said rollers including shafts axially disposed on said head and arranged for eccentric movement trans-
versely of the axis of the head.

4. In a burr remover, a rotatable head, a plu-
5 rality of burr removers mounted thereon to swing outwardly against the burrs due to centrifugal force upon rotation of said head, and means to control the swinging movement of any one re-
10 mover to the same movement as the other re-
movers including eccentric arms swingable trans-
versely of the axis of said head.

5. A burr remover head comprising spaced end plates, bolts connecting said plates, a pair of arms pivoted on each bolt, a shaft carried by 15 each pair of arms, a pinion gear carried by one of said plates, and teeth on one arm of each pair which are engaged with said pinion so that all of said removers are restrained to the same amount of movement. 20
